GUNNAR C. ENGSTRAND, OF NEW YORK, N. Y., ASSIGNEE, BY MESNE ASSIGNMENTS,
TO SALVAGE PROCESS CORPORATION, OF NEW YORK, N. Y., A CORPORATION OF
NEW YORK

APPARATUS FOR PUMPING VISCOUS FLUIDS

Application filed October 28, 1925. Serial No. 65,477.

My invention relates to a pumping apparatus for transference of materials from one point of storage to another. More particularly, my invention relates to the transference of materials from the tanks of vessels to other points of storage or readily movable containers. Preferably, my invention has utility with viscous, sticky, semi-solid materials which may be desired to be pumped, or otherwise removed from one storage chamber to another.

An object of the invention is to draw viscous fluid through a transmission line in such an improved state as to lower its frictional resistance more than heretofore has been possible whereby a much less powerful pressure reducing means is required.

A further object is to pass the fluid through the discharge end of the line still in such a state of mobility that it flows freely and avoids clogging the discharge line.

A still further object is to discharge the fluid continuously without admitting air into the discharge line to interrupt the action of the vacuum producing means and without the necessity of keeping the end of the discharge line immersed in liquid to seal it.

According to the invention the above objects are achieved by providing a transmission line, one end of which is provided with an intake nozzle and the other end of which extends to any suitable point of discharge such as an oil tank or barge alongside of the vessel from which the viscous fluid is to be removed. A pressure reducing means, preferably a steam operated air exhauster of the aspirator type is connected to the line, preferably at the top of the outboard section of the line and known as the discharge leg. The inboard section of the line extending down into the vessel is designated as a suction leg and is provided with means adjacent the lower end permitting the introduction of water and air into the fluid as it is drawn into the suction leg to form an aerated watery mixture rendering the fluid unusually mobile so that its resistance to movement through the line is materially reduced, thus requiring much less power in the pressure reducing means to draw the liquid up through the

suction leg than if the fluid were mixed with air only. As the fluid is drawn to the top of the suction leg it enters the discharge leg and drops therethrough due to its own momentum. The discharge leg is provided with means at its lower end to prevent the admission of air into this end while at the same time permitting the fluid to flow freely out. The fluid in the discharge leg may be kept more mobile by providing heating means around this portion of the line.

Any air entrained in the liquid is by-passed from the fluid at the top of the discharge leg, passing through the connection to the aspirator.

By having the discharge end of the line provided with means to permit the outflow of the fluid but to prevent the inflow of air, it is not necessary to have this end of the line dipping into liquid to seal it.

In the drawing—

Figure 1 shows the general pumping arrangement.

Figures 2, 3 and 4 show the detail construction of the pumping apparatus on an enlarged scale.

Referring to the drawing in which the reference characters designate corresponding parts, 1 represents the vessel from which the fuel oil residue is pumped. Alongside the vessel the sloop barge 2 is moored.

A flexible hose 3 forming a suction leg is shown connecting the ship tank 4 with the sloop barge, and this transmission line is connected to the separator 5 which is conveniently connected to the mast 6 mounted on the barge 2.

The vertical discharge leg 7 is attached to the bottom of the separator 5, and the side outlet 8 of the separator is connected to the air exhauster 9 by means of pipe line 10, thus by-passing the exhauster 9 from the discharge leg at the top thereof.

The air exhauster is of the conventional steam aspirator type, the steam being supplied through the hose connection 11 and discharged to the atmosphere through the pipe 12.

The discharge leg 7 is shown surrounded by a steam jacket 13, supplied with steam con-

nections 14 and 15, through which a steam circulation is established.

Near to the end the discharge leg 7 is provided with a horizontal check clapper valve 5 16.

The nozzle 17 of the suction leg 3 is shown with a restricted inlet nipple 18 and the air openings 19 are drilled in the nozzle body.

A water inlet pipe 20 provided with a regulating valve 21 is also secured into the nozzle body, the pipe 20 being disposed to introduce the water at right angles to the suction leg.

The restricted end of the nozzle 17 is shown slightly submerged in the oil residue 22 inside the ship tank 4.

Inside the separator 5 the suction leg 3 terminates in a short pipe 23 at a distance above the vertical discharge leg 7.

Around the pipe 23 at a point below the 20 side outlet 8 the screener 24 is attached.

The operation and method of the pumping is as follows:—

The nozzle is slightly inserted in the oil residue to be pumped, care being taken not 25 to submerge the airholes 19, and the steam actuated air exhauster is started.

The water admittance is regulated by means of setting the valve 21 properly.

The mixture of water and residue will seal 30 the intake and with the intake end sealed in this manner the pressure in the line is being reduced more quickly than the frictional resistance of the ascending liquid column, which resistance is in direct proportion to the 35 height of the column. A reduced pressure will soon be reached at which the column will part at the air admittance, and the column slug will be propelled by the air filling in behind and will rush through the transmission 40 hose with a great velocity.

In reaching the separator 5 the slug will discharge through the separator into the discharge leg 7, without loss of momentum, while the air will be by-passed through the screener 45 24 and separator outlet 8 into the air exhauster 9.

The function of the check valve 16 is to prevent any air from being drawn up through the discharge leg 7 and thus interrupt the operation, thus the discharge end of the line need not be immersed in liquid to seal it and consequently it is not necessary that it be associated with a tank or a barge or other receptacle containing liquid into 55 which the discharge end would otherwise have to be dipped. This is of considerable advantage because the back pressure head due to the discharge end being sometimes several feet below the level of the liquid in 60 a tank is avoided and also the disadvantage which occurs when the discharge end dips into a barge and is only a few inches below the surface of the liquid therein and the barge is rising and falling on the water alongside 65 of the vessel causing the end of the discharge

line sometimes to be below the level of the fluid in the barge and sometimes to be above the level of the fluid thus causing an intermittent break in the pumping action and materially affecting the operation.

When the material pumped is very viscous, as is the case in cold weather, steam is furnished to the steam jacket 13, in order to reduce the viscosity of the material and prevent the clogging up of the discharge leg.

It is to be noted that the regulating valve 21 has to be set just so as to admit the proper amount of water that will form a mixture with the particular kind of oil residue which is to be pumped.

It is also to be noted that the nozzle inlet 18 shall not be too deeply inserted into the liquid material as it has been found that the amount of air which passes through the openings 19 is inadequate to fill in behind the column slugs.

Therefore, the extra amount of air needed at this instant will have to be admitted through the intake end proper.

It is also to be noted in this connection that the amount of air admitted to the line at this instant is much larger than the amount of air which the air exhauster is able to draw out and the vacuum is accordingly reduced in the transmission hose. With the pressure lowered another water in oil column gets a chance to form at the intake end whereupon the operation is automatically repeated.

I claim:

1. A pumping apparatus for viscous fluids comprising a transmission line having a suction leg and a discharge leg, pressure reducing means connected to the line at a point near the top of the discharge leg, means for admitting water and air into the suction leg at the intake end thereof, and means at the discharge end of the line to prevent air flowing in while permitting fluid to flow out.

2. A pumping apparatus for viscous fluids comprising a transmission line having a suction leg and a discharge leg, means for exhausting air from said line, means at the discharge end of the line to prevent the entrance of air while permitting fluid to flow out, means at the intake end of the line to permit air to be introduced into the fluid and means for injecting a stream of water into said line near said intake at an angle to the direction of flow of fluid therein.

3. A pumping apparatus for viscous fluids comprising a transmission line having a suction leg and a discharge leg, pressure reducing means connected to the line at the top of the discharge leg, means in the discharge leg to permit fluid to flow out but preventing the entrance of air, a nozzle in the suction leg at the intake end thereof having apertures to permit air to be drawn in, and means adjacent the nozzle to introduce a stream of

water into the fluid transverse to the direction of flow of fluid therein.

4. A pumping apparatus for viscous fluids comprising a transmission line having a suction leg and a discharge leg, said discharge leg having a separating chamber into which an end of the suction leg projects, an air exhausting means connected to the discharge leg above the level of the adjacent end of the suction leg, heating means disposed around the discharge leg below the separating chamber, a check valve in the discharge leg at the lower end thereof to prevent air entering said leg, a restricted nozzle at the intake end of the suction leg, said intake end having air admitting apertures therein, and means connected to the suction leg above said apertures to admit water into the fluid in a direction at right angles to its direction of flow.
